SHOE STITCHING MECHANISM

Eugene G. Wolf, St. Louis, Mo., assignor to Landis Machine Company, St. Louis, Mo., a corporation of Missouri

Application April 25, 1932, Serial No. 607,305

9 Claims. (Cl. 112—47)

The invention relates to shoe stitching machinery and has been developed particularly in connection with lock stitch McKay machines although certain features of the invention may be used in other stitchers.

The invention consists in novel features of the presser foot and work feeding mechanism.

The objects of the invention are to provide better means for clamping the work between the horn 10 and the presser foot, to facilitate the penetration of the work by the needle and to improve the appearance of the work by avoiding the production of feed point marks between the stitches, and to make the stitching more even and the length of 15 stitches more easily adjusted. These objects are attained, briefly, by elongating the presser foot and recessing it laterally to receive the needle and feed point; by adjusting the feed point actuating mechanism so that the feed point always terminates its feeding movement in the axis of the 20 needle; and by simplifying the stitch length adjusting means.

A structure embodying these features is illustrated in the accompanying drawings in which—

25 Figure 1 is a front view of the needle bar, presser foot bar, feed mechanism, and adjacent horn of a McKay machine with the point of the horn directed to the left.

Figure 2 is a side elevation of the same parts 30 looking at the right hand side of the machine.

Figure 3 is a side view of the upper portion of 35 the feed actuator lever showing its connection to its driving link and viewing these parts from the left hand side of the machine.

Figure 4 is a detail of some of the parts illustrated in Figure 1 which shows them in a different operating position.

Figure 5 is a horizontal section taken on the line 40 5—5 of Figure 1 with the feed point removed.

45 The general arrangement illustrated corresponds to the structure of my copending application, Serial No. 579,610, filed December 7, 1931, and embodies a frame head 1, a drive shaft 2, a rotatable horn 3, a vertically reciprocating needle bar 4, and a presser foot bar 5.

The presser foot 6 has its horizontal portion elongated so as to extend from the right hand side of the needle to the left hand side thereof overlying the tip of the horn 3 and this portion of 50 the foot is provided with a lateral recess 7 (Figure 5) which opens towards the front of the machine and accommodates the needle 8 and the feed point 9 of the feeding element 10 which is mounted on the lower end of an actuating lever 55 11 pivoted at 12 to a boss 5a on the presser foot

bar 5 and driven by an actuating link 13 connected to a lever 14 which is pivoted at its lower end 15 on the machine head 1 and is oscillated at its upper end by an offset member 16 which has a slide 16a, engaging the upper end of lever 14, and a slotted tongue 16b by which the member is adjustably secured by stud 16c to a shaft S provided with a crank 18 which carries a cam roller 19 engaging the groove 20 of the cam wheel 21 mounted on the drive shaft 2. Shaft S has projecting ears 17 between which tongue 16b fits. Stud 16c is readily accessible from the front of the machine and by loosening this stud, the operator may easily raise or lower member 16 on shaft S to vary the oscillation of lever 14 and the throw of lever 11 to vary the length of feeding movement which controls the length of stitch.

A pin 22 connects link 13 and lever 11 and the axes of the bearing portions of this pin engaging the link and lever, respectively, are offset or disposed eccentrically of each other. By loosening the lock nuts on the threaded ends of the pin and rotating the pin on its axis to a different angular position, the offset bearings will shift the end of link 13 transversely of lever 11 varying the effective length of the connection between levers 11 and 14 and the relative position of the levers whereby the relation between element 10 and lever 14 can be adjusted so that at the end of the feeding movement the point 9 will lie in the axis A of the needle, as indicated in Figure 4. This desirable terminus 25 of the feed point may be maintained irrespective of the extent of feeding movement which determines the length of the stitch and is controlled by the setting of member 16 on shaft 17. The feed 30 point always remains within the recess 7 in the presser foot.

Since the feed point functions by digging into the work slightly and since it terminates its stroke in the axis of the needle, it provides a depression 40 for the needle to enter which tends to guide the needle and facilitates its passage through the work. Also, the surface of the leather will be free of feed point marks intermediate the stitches such as would be produced if the feed point depression were not in the needle axis.

By elongating the work engaging portion of the presser foot, I provide increased contact area of the presser foot on the sole which tends to eliminate any presser foot marks on the sole; 50 holds the sole flat against the pull of the needle and thread; and avoids the end of the presser foot digging into the horn when work is removed from the latter and irrespective of the angular position of the horn.

It is believed that the above specification and the accompanying drawings clearly describe the novel features of my machine and it will be understood that the details may be varied without departing from the spirit of my invention and I contemplate the exclusive use of such modifications as come within the scope of my claims.

What is claimed is:

5. In a machine of the class described, a needle, work feeding mechanism including a reciprocating work engaging feed point, and means for aligning said feed point with the axis of said needle at the end of the feeding movement, said work feeding mechanism including a lever upon which said feed point is carried and a member pivoted to said lever for oscillating the same, the connection between said lever and member comprising a pin having parts disposed eccentrically 10 of each other and movable about their axis to align the feed point with the axis of the needle. 5
10. In a machine of the class described, a work carrying rotatable horn having a substantially horizontal work engaging tip, a presser foot having an elongated work engaging portion overlying said tip irrespective of the angular position of the horn and provided with an elongated recess 15 opening towards the front of the machine, and a work feeding element projecting into said recess and reciprocating back and forth therein transversely of the machine. 15
15. In a machine of the class described, a work carrying rotatable horn having a substantially horizontal work engaging tip, a presser foot having an elongated work engaging portion overlying said tip irrespective of the angular position of the horn and provided with an elongated recess 20 opening towards the front of the machine, and a work feeding element projecting into said recess and reciprocating back and forth therein transversely of the machine. 20
20. In a machine of the class described, a work carrying rotatable horn having a substantially horizontal work engaging tip, a presser foot having an elongated work engaging portion overlying said tip irrespective of the angular position of the horn and provided with an elongated recess 25 opening towards the front of the machine, a needle which alternately projects through said recess into said horn and is withdrawn therefrom, and a work feeding element projecting into said recess and reciprocating back and forth therein transversely of the front of the machine. 25
25. In a machine of the class described, work feeding mechanism including a reciprocating point arranged to dig into the work to engage and feed the same, and a presser foot on the same side of the work as said point and arranged to overlie and bear against the work throughout the length of, across the front of, and behind the stroke of said point. 30
30. In a machine of the class described, work feeding mechanism including a reciprocating point arranged to dig into the work to engage and feed the same, and a presser foot on the same side of the work as said point and arranged to overlie and bear against the work throughout the length of, across the front of, and behind the stroke of said point. 35
35. In a machine of the class described, a presser foot bar, a horizontal work engaging foot carried by said bar and elongated transversely of the machine and having an elongated recess, work feeding mechanism comprising a lever pivoted on said bar and a work engaging element carried by said lever and projecting into said recess and movable longitudinally thereof by oscillation of said lever. 40
40. In a machine of the class described, a feed cam, a shaft with a crank engaging said cam, an arm mounted on said shaft and adjustable radially thereof to vary the length of the stitch, a lever having a stationary pivot on the machine frame, said lever being oscillated by said arm, a feed point mounting lever, a connection between said levers, and means for varying the effective 45 length of said connection to vary the relation between said levers whereby the terminal position of the feed point may be maintained irrespective of the adjustment of said arm. 45
45. In a machine of the class described, a work engaging feed point, a lever for mounting and reciprocating said feed point, a feed cam, means driven by said cam and actuating said lever and including a crank shaft of which the crank is adjustable transversely of the shaft to vary the extent of the feeding movement. 50
50. In a machine of the class described, a feed cam, a shaft oscillated by said cam, a crank slidably mounted on said shaft to vary the crank throw, a work engaging feed point driven by said crank, and means for securing said crank in desired position on said shaft, said means comprising a stud with its head readily accessible to an operator at the front of the machine. 55
55. A structure as set forth in claim 6 in which the connection between the levers comprises a link and a pin extending through said link and one of said levers and having individual bearing portions engaging said link and lever, respectively, said portions being disposed eccentrically of each other. 60
